UNITED STATES PATENT OFFICE.

LORENZO S. GRAVES, OF ROCHESTER, NEW YORK, ASSIGNOR TO LORENZO S. GRAVES & SON, OF SAME PLACE.

SCREW-ELEVATOR.

SPECIFICATION forming part of Letters Patent No. 309,538, dated December 23, 1884.

Application filed April 5, 1884. (No model.)

To all whom it may concern:

Be it known that I, LORENZO S. GRAVES, of Rochester, in the county of Monroe and State of New York, have invented certain Improvements in Elevators, of which the following is a specification, reference being had to the accompanying drawings.

My invention relates to certain improvements in elevators of that class in which motion is communicated to the winding-drum by means of a revolving screw and screw-gear, and which improvements are fully described in the following specification, the novel features thereof being specified in the claims hereunto annexed.

My improvements in elevators are represented in the accompanying drawings, in which Figure 1 is a side view of an elevator in the position occupied by it when in use, attached to the ceiling or other suitable support. Fig. 2 represents the same as seen from below. Figs. 3 and 4 show the mode of attaching the brake-shoe to the brake-lever. Fig. 5 is a section on the line $y-y$, Figs. 1 and 25. Figs. 6 and 7 are views of the cam on the shifter-shaft, as seen from the inside. Fig. 8 is a section of the cam on the line $z-z$, Fig. 6. Fig. 9 is a side view of the traveling nut on the shifter-shaft. Fig. 10 shows the automatic 30 stop-motion on the shifter-shaft. Fig. 11 is a side view of the cam and roller which operate the brake.

In the accompanying drawings, A A' are the side frames of my improved elevator; B, 35 the cable-drum; C, the screw; D, the screw-gear; E, the cam for shifting the belts from the loose pulleys K and N onto the tight pulley L; F, the wheel for the starting-rope; H, the brake-wheel, and O the hanger at the outer 40 end of the screw-shaft d. The side frames, A A', are made of suitable size and shape to support the winding-drum B, which revolves therein in suitable bearings, f f, at each end of the drum. The drum is preferably cast in 45 one piece, having on each end the journals e e, fitted within the bearings f f, and its outer surface being provided with a spiral groove or grooves for the reception of the cable or cables. The worm-gear D consists of a suitable toothed ring, secured to the drum inside

of one of the journals f by means of screws or bolts. The screw C is arranged to mesh with the teeth of the worm-gear, being placed on the shaft d at right angles with the axis of the drum and above the screw-gear or between it and the ceiling or support to which the elevator is attached. The screw C is forged on or otherwise secured to the worm-shaft d, which also carries the tight pulley L, loose pulleys K and N, and the brake-wheel H. The worm-shaft revolves in suitable bearings placed on the inner face of the frame A' at each side of the screw, its outer end being supported in a suitable bearing, w, carried by the hanger O.

In the practical operation of the machine motion is imparted to the screw-shaft d by two belts traveling in opposite directions, which are shifted onto the tight pulley L when the elevator is at work, but which run on the loose pulleys K and N when the machine is not in use. As the screw-shaft revolves in one direction or the other it causes the winding-drum to rotate and to wind or unwind the lifting-cable R, Fig. 1, thereby raising or lowering an elevator-platform which is attached to the end of the cable, which passes over a carrying-wheel. The strain of the weight on the cable is transmitted to the shaft by the screw-gear and screw, causing an end-thrust which is received by a suitable thrust-bearing, w, at the end of the screw-shaft, supported by the hanger O. This end-thrust may be sustained by a collar or collars on the shaft or by a screw, y, Fig. 1, bearing against the end of the shaft. The belts are separately shifted from the loose pulleys to the tight pulley, or back again, by means of the shifters i j, on the ends of the sliding shifter-rods g and h, which are operated from the cam E by means of the levers v and x, Figs. 1, 6, and 7. The shifter-rods are arranged to slide in suitable ways or guides, l l, on the frame of the machine. The lever v is pivoted on a stud at e', attached to the frame, its upper end being fitted into a block, r', secured on the sliding shifter-rod g, so that as the lever swings, as indicated by the full and dotted lines in Fig. 1, the shifter is caused to slide in the guides l l and to shift the belt from the loose pulley N to the tight

pulley L. In a similar manner the lever x is arranged to transmit motion from the cam E to the shifter-rod h, being pivoted to the frame at f', Figs. 1 and 6, and connected to the rod 5 by the block s', Fig. 1. The shifter-rod h operates to shift the belt from the pulley K to the pulley L, or vice versa. At their lower ends the lever v and x are provided with the rollers n' and h', which are fitted to the cam- 10 groove c in the inner face of the cam E. The cam E is secured to the shifter-shaft a, which passes centrally through the drum B, the journals e e of which are bored out to receive it. The shifter-shaft a carries at one end the 15 wheel or pulley F, to which the starting-rope is attached, by means of which a partial revolution is given to the cam E in either direction, thereby shifting the up or down belt onto or off the tight pulley L. The starting-rope is 20 carried about suitable pulleys, if necessary, and passes up and down within the elevator-well, being arranged so as to be conveniently under the control of a person riding on the elevator-platform, as is customary in this class 25 of machines. The shifter-shaft a also carries the automatic stop-motion S T T', located within the cable-drum, by which the motion of the elevator is controlled when the platform reaches the top or bottom of the elevator-well.

30 The operation of the cam E will be readily understood by an inspection of Figs. 6 and 7 of the drawings. The cam is provided with a cam-groove, a portion of which, c, extending half-way around the cam, is circular, while the 35 other parts, c' c'', are curved inward toward the shifter-shaft for about one-fourth of a revolution, so that when the shifter-shaft is rotated in either direction for a quarter of a revolution, one of the levers is caused to swing on its 40 pivot, thereby shifting the corresponding belt from the loose to the tight pulley, while the other lever is held at rest, and the belt which it controls will remain on the loose pulley over which it runs. Thus in Fig. 6 a quarter-turn 45 of the shifter-shaft and cam causes the end of the lever x to swing inward, as indicated in Fig. 7, thereby shifting the belt from the pulley K onto the tight pulley L, while the end of the lever v remains stationary, its roller n' 50 running in the circular part e of the cam-groove.

I claim—

1. The combination, with the revolving cable-drum of an elevator, of a shifter-shaft ex-

tending centrally through the drum, and provided with the automatic stop-motion located 55 inside the drum, substantially as and for the purposes set forth.

2. The combination, with the revolving cable-drum of an elevator, provided with hollow journals e e, of the centrally-located shifter-shaft a, provided with the automatic stop-motion inside the drum, substantially as and for the purposes set forth.

3. The combination, with the revolving cable-drum B of an elevator, of the centrally-located threaded shifter-shaft a, traveling nut S, 60 connected with the drum so as to revolve therewith, and stops T and T' on each side the traveling nut, substantially as described.

4. The combination, with the revolving cable-drum of an elevator, of the automatic stop-motion located within the drum, substantially as described.

5. The combination, with the revolving elevator-drum B, of the centrally-located threaded shifter-shaft a, clamp-nuts T and T', and traveling nut S, connected to the interior of the drum so as to revolve therewith, substantially as described.

6. The combination, with the revolving elevator-drum B, of the centrally-located shifter-shaft a, provided with the automatic stop-motion within the drum, screw-gear D, screw and screw-shaft C d, brake-wheel H on the worm-shaft, brake I, cam m, spring t, and connecting 85 mechanism, as described, arranged to permit the spring to apply the brake under the control of the stop-motion, substantially as and for the purposes set forth.

7. The combination, with the drum B, of the screw-gear D, screw and screw-shaft C d, shifter-shaft a, provided with cam m, brake-wheel H, 90 brake-shoe I, adjusting-screw c', spring t, and connecting-levers, substantially as described.

8. The combination, in an elevator located 95 so as to permit the cable to pass from the winding-drum directly upward in the elevator-well, of the winding-drum B, screw-gear D, and screw-shaft d, placed above the screw-gear, and provided with the thrust-bearing W at 100 its outer end, substantially as described.

LORENZO S. GRAVES.
